UNITED STATES PATENT OFFICE.

GEORGE J. SHIMER, OF FREEMANSBURG, ASSIGNOR TO SAMUEL J. SHIMER,
OF MILTON, PENNSYLVANIA.

CUTTER-HEAD.

SPECIFICATION forming part of Letters Patent No. 293,529, dated February 12, 1884.

Application filed July 18, 1883. (No model.)

To all whom it may concern:

Be it known that I, GEORGE J. SHIMER, a citizen of the United States of America, residing at Freemansburg, in the county of Northampton and State of Pennsylvania, have invented certain new and useful Improvements 5 in Cutter-Heads, and I do hereby declare the following to be a full, clear, and exact description of the invention, such as will enable others skilled in the art to which it appertains to make 10 and use the same.

This invention relates to improvements in cutter-heads for matching, grooving, and finishing the edges of lumber, of that class composed of two sections operating conjointly, and which are vertically adjustable. In this respect 15 my invention has special application to that kind of cutter-head shown and described in Letters Patent No. 241,432, dated May 10, 1881, 20 granted to Geo. J. and Samuel J. Shimer.

My invention consists, first, in a novel locking device, whereby the removable section of the cutter-head is secured in any determined 25 position in relation to the fixed section; and, second, in the novel construction and combination of parts, as will be hereinafter described and specifically claimed.

In the accompanying drawings, forming a 30 part of this specification, Figure 1 is a perspective view of a cutter-head of my improved construction and provided with my improved locking device. Fig. 2 is a bottom view of the cutter-head. Fig. 3 is a perspective view of the adjustable section of the cutter-head supplied with bits or cutters. Fig. 4 is a similar 35 view of the stationary section of the cutter-head, showing fully the coiled spring about the hub and slot for set-screw. Fig. 5 is a view of the locking-nut. Fig. 6 is a vertical sectional view, showing the relative position of the parts conjointly arranged; and Fig. 7 is a view of a cutter-bit.

The letter A represents the cutter-head, composed of two sections or parts—the lower or stationary section, B, and the upper or adjustable section, C. The section B (see Fig. 4) is constructed with a central hub, D, and bored to suit the dimensions of the rotating spindle. This hub is provided with a vertical slot, a,

in which a set-screw passes from the adjustable section, as hereinafter more fully stated, 50 against the spindle, and has in its upper portion exterior screw-threads for the purpose of receiving the locking-nut. The base of this stationary section B is formed with the circular walls b, extending between the bit-holders, 55 and forming against their inner faces a seat or shoulder. The base of the hub and tool-holders is solid, and the tool-holders E E' are made of such strength and dimensions as to receive the 60 tools and meet any strain the required work may demand. They are arranged, as shown, 65 at right angles to the axis of the rotation, directly opposite each other and on the same plane. The section C (see Fig. 3) is constructed with a depending central sleeve, F, of such exterior diameter as to pass readily over the hub of the stationary section and to permit of 70 easy vertical adjustment, as desired, and is also constructed with the circular walls c, connecting the re-enforced side segments, G and G', arranged directly opposite each other, and carrying the cutter-tools. Between the sleeve 75 F and the walls c and side segments, G and G', is a space which the coil-spring fits, the section 80 resting on the same. In the side wall of this section, being the one opposite the slot in the hub of the lower section, is fitted a set-screw, H, which extends through the wall and in the slot a, against the spindle, and fixes the tool 85 securely in place. This section C has also formed on the upper surface, about the bore, the wall I, in turn formed with the V-shaped 90 projections g, or their equivalents, substantially as shown, for the purposes hereinafter 85 stated. The side segments or bit-holders of the respective sections are formed with the mortises d, to receive the bits or cutters, and provided with set-screws e, adapted to fit in the screw-holes f f' at or near each end, on 95 the upper surface, to secure the bits or cutters to their seats, according to the direction of rotation. The mortises in the respective sections are, as usual, arranged parallel to each other, and on the same plane. Arranged within the circular walls of the lower section and loosely about the hub thereof is the coil-spring K, or its equivalent, which, when the upper section

of the cutter-head is passed over the hub of the lower section, fits about the depending sleeve F of the former and exerts sufficient force to prevent the uninterrupted descent of 5 the adjustable section to its downward limit, and serves to press it against the locking-nut.

The letter L represents a locking-nut provided with female screw-threads fitting the screw-threads in the hub of the lower section, 10 and formed on its under face with V-shaped projections h, or their equivalent, corresponding to the spaces between the projections g on the wall I of the upper section of the cutter. It will now be observed that when the nut L 15 is screwed down on the wall I the action of the spring keeps the nut and the section together, and the contact of the uneven surfaces of these parts effectually prevents the nut from becoming loosened by the rotation of the cutter-head.

The parts constituting the cutter-head are put together in the following manner: The coil-spring is passed over the hub of the lower section, finding its seat on the base of the chamber between the hub and the side wall thereof, 25 after which the adjustable section is passed over the hub of the lower section, with the segments at right angles to those of the latter, and with the set-screw on the side next the slot in 30 the hub, the spring passing up in the space between the depending sleeve of the section and the walls until it rests against the roof of the chamber between them, when the locking-nut is applied and screwed to such position as 35 will give the desired adjustment of the sections. The bits of the tool are fixed in place by the set-screws and adjusted in the well-known manner.

By the construction of the parts as described, so that the spring-space is round instead of 40 square, I am enabled to make smaller heads of greater strength than heretofore, where the spring-space is square.

What I claim as my invention, and desire to secure by Letters Patent, is—

1. In a cutter-head, the combination, with 45 the lower section having the elongated screw-threaded hub, of the upper section provided with a central aperture to fit over said hub, and having on its upper surface a corrugated collar or wall, I, surrounding said aperture, 50 the elastic cushion arranged between the upper and lower sections, and the nut L, screwed upon the central hub, and having its under surface adapted to form a locking-engagement with the said collar I, substantially as described. 55

2. A cutter-head composed of two parts capable of vertical adjustment, the under section whereof is formed with a central screw-threaded hub and circular side walls, and the upper section whereof is formed with a depending sleeve and circular side walls, and having formed on its upper surface and around its central opening a circular wall with V-shaped projections or their equivalents, in combination with a locking-nut formed with V-shaped 60 projections or their equivalents on its under surface, substantially as described. 65

3. The combination, with the lower section provided with a central hub, in which is formed a vertical slot, a, of the upper section fitting 70 over said hub, and provided with the set-screw H, arranged to pass through the slot in the hub, the elastic cushion between the two sections, and suitable means for securing the upper section to the hub, substantially as described. 75

In testimony whereof I affix my signature in presence of two witnesses.

GEORGE J. SHIMER.
